UNITED STATES PATENT OFFICE.

CORNELIUS J. PHILLIPS, OF NEW YORK, N. Y.

COMBINED PLUG AND FERRULE FOR WASH-TRAY CONNECTIONS.

SPECIFICATION forming part of Letters Patent No. 383,982, dated June 5, 1888.

Application filed May 18, 1887. Serial No. 238,611. (No model.)

To all whom it may concern:

Be it known that I, CORNELIUS J. PHILLIPS, of the city, county, and State of New York, have invented a new and Improved Combined 5 Plug and Ferrule for Wash-Tray Connections, of which the following is a full, clear, and exact description.

The object of my invention is to provide such construction of wash-tray and similar 10 connections for connecting the tray with the waste-pipe as to avoid the use of a coupling, and such that any length of connection may be used.

Reference is to be had to the accompanying 15 drawings, forming a part of this specification, in which similar letters of reference indicate corresponding parts in both the figures.

Figure 1 is a detailed plan view of a part of a wash-tub or similar receptacle having my 20 invention applied thereto, and Fig. 2 is a broken sectional elevation of the same on the line *x x* of Fig. 1.

A represents the pipe-connection which connects the tray *B* with a waste-pipe. (Not 25 shown.) This pipe passes directly up through the aperture *a* in the tray *B*, and is externally screw-threaded below the tray *B*, as shown at *b*. Upon the screw-threaded portion is placed 30 firmly against the bottom of the tray *B*. The upper end of the pipe *A* is internally screw-threaded, as shown at *e*, and in it is screwed the plug-bushing or ferrule *D*. This is externally screw-threaded to match the internal

screw-threads, *e*, and is formed with the grating 35 *e'* and with the upper flange, *d*, between which and the bottom of the tray the packing *f* is placed, as shown in Fig. 2. In the flange *d* are formed the small holes *i i*, for convenience in inserting and removing the ferrule *D* from 40 pipe *A*. The outer surface of the pipe *A*, where it passes through the bottom of the tray, is plain, as shown at *c*², and of slightly greater diameter than the lower part of the pipe, to fit and form a close joint with the aperture in the bottom of the tray *B*. 45

The ferrule *D* by this construction is made to serve the double purpose of ferrule and holder for the pipe *A* in the tray, and it furnishes the resisting-flange for the drawing action upon the pipe *A* by the jam-nut *C*, and the pipe *A* may be made of any length continuous, and no coupling is required. 50

Having thus described my invention, what I claim as new, and desire to secure by Letters 55 Patent, is—

The pipe *A*, internally screw-threaded at its upper end, enlarged in diameter at *c*², and externally screw-threaded at *b*, in combination with the ferrule *D*, formed with flange *d*, 60 and externally screw-threaded to enter the top of the pipe, and the jam-nut *C*, placed upon the threads *b*, substantially as shown and described.

CORNELIUS J. PHILLIPS.
